UNITED STATES PATENT OFFICE.

RALPH HARVEY, OF ETNA, PENNSYLVANIA.

WASHING PROCESS AND MACHINE THEREFOR.

Application filed December 11, 1923. Serial No. 679,945.

To all whom it may concern:

Be it known that I, RALPH HARVEY, a citizen of the United States, residing at Etna, in the county of Allegheny and State 5 of Pennsylvania, have invented certain new and useful Improvements in Washing Processes and Machines Therefor, of which the following is a specification.

This invention relates to a washing process and machine therefor, and more in particular to such a process and machine intended to be used for washing tuberous vegetables, such as beets, carrots, potatoes, etc.

15 The primary object of this invention is to provide a washing machine operating in accordance with my new process for washing great quantities of tuberous vegetables thoroughly and rapidly. Another object is 20 to provide such a machine which automatically discharges the washed vegetables. A further object is to provide a machine which is of simple and rugged construction and which can be manufactured at relatively 25 low cost. Additional features and advantages of this invention will appear from the following description considered in connection with the accompanying drawings forming part of this application.

30 In the drawings:

Fig. 1 is a longitudinal section taken substantially through the center of the washing machine.

Fig. 2 is a cross section taken on line 35 2—2, Fig. 1.

Fig. 3 is a fragmentary perspective view showing the feeding end of the washing machine constructed for electric drive.

Fig. 4 is a perspective view of the rotating wash-drum used in the machine.

Fig. 5 is an enlarged view, partly in section, showing the preferred type of water spray nozzles used in the machine.

Fig. 6 is a fragmentary perspective view 45 showing the discharge end of the machine.

Fig. 7 is a fragmentary perspective view of the discharge end of the wash-drum.

Fig. 8 is a fractional view showing one 50 method of feeding the machine by means of a hopper and endless belt conveyor.

Fig. 9 is a cross section taken on line 9—9, Fig. 8.

Fig. 10 is a cross section taken on line 10—10, Fig. 8.

Referring to the drawings, my washing machine comprises a water container or vat

1, of suitable size and shape, mounted upon feet 2 secured thereto in any desired manner. The open top of this vat may be closed by means of a cover 3, preferably secured thereon by means of the hinges 4.

Placed within the latter is a drum 5 made of evenly spaced slats 6 secured on the circumference of the spiders 7 and 8, and open at both ends. This drum is supported on a shaft 9, traversing the spiders, and is held securely in position thereon by means of set screws 10 engaging the hubs 11 of the spiders. This shaft is mounted for rotation in the front and rear bearings 12 and 13 which are firmly bolted, or otherwise fastened, to the front and rear ends 14 and 15 respectively of the vat. The shaft may be rotated in any suitable manner, such as by hand, belt drive or preferably by means of the electric motor 16 connected thereto by means of the worm 17 and the gear 18, securely held on the shaft either by a key or a set screw such as indicated by the numeral 19. Said shaft is also held against longitudinal displacement by means of said gear and a collar 20 placed at the rear end of the shaft and held thereon by the set screw 21.

Positioned intermediate the spiders 7 and 8 are the lifting blades 22 disposed radially within the drum, and in the space intermediate the rear spider and the rear end of the wash-drum are the discharging blades 23 which are disposed within the drum at an acute angle with the circumference thereof, for the purpose of retaining the washed vegetables until they roll off, by the force of gravity, upon a discharging trough 24 which communicates with the discharge chute 25 through an aperture 26 suitably provided in the upper part of the rear end of the vat.

The vegetables to be cleaned are introduced into the drum through an opening 27 placed adjacent the top of the front end of the vat. A chute 28 which, when not in use, may be folded over the cover of the vat, by means of the special construction illustrated in Fig. 1, is preferably used to facilitate the feeding of vegetables to the washing machine. As shown therein, the chute is supported by means of links 29 hingedly connected at their upper ends to the hinge-lugs 30, fastened to the vat; said links being secured at their lower ends to the chute by means of the pins 31, engaging

the slots 32 cut in the sides 33 of the chute. These slots are supplied to enable the extraction of the chute from the vat prior to folding it over the vat-cover. A stop-lug 5 34 is also shown fastened to the underside of the chute for the purpose of limiting the movement of the latter into the vat and drum. The vegetables may be shovelled directly onto the chute, or else into a hopper-bin 35 placed above the end of the chute.

10 The water for washing is led into the vat by means of a supply pipe 36, connected to the water main, and divided in two or more branches 37 and 38 supported by the front end 15 of the vat and supplied with the necessary and usual fittings shown in Fig. 3; said branches terminating at their inner ends with the horizontally disposed flat nozzles 39, from which a sheet-like spray of water 20 is discharged across the drum. The amount of water in the vat is determined by the over-flow pipe connection 40 which is situated at a suitable distance below the nozzles. The bottom of the vat is inclined towards 25 the front end to enable the drainage of the muddy water through the drain plug 41. As will be seen in Figs. 1 and 6, the discharge-chute is partly closed at its outer end by an apron 42; this is done to prevent excessive splashing of the water and to limit 30 the bounding of the discharged vegetables.

The feeding mechanism shown in Figs. 8, 9 and 10, represents one of the many alternative constructions which might be employed to serve the vegetables into the washing machine. It comprises a receiving hopper 43 discharging into the open trough 44 at the bottom of which operates the conveyor belt 45 running over the rollers 46 and 40 47, the shafts 48 of which are mounted in the bearing supports 49 secured on the base board 50 fastened to the front end of the vat by means of the angle support 51 and the braces 52. The motive power for the conveyor 45 may be applied to either one of the roller shafts in any suitable and desired manner, to cause the conveyor belt to move in the direction indicated by the arrows in Fig. 8.

50 Having thus described the essential parts of the washing machine, its mode of operation will be readily understood and is as follows:

When vegetables are to be washed, the 55 drum is first rotated and the water supply turned on. The vegetables are then introduced into the drum, either by means of a chute or conveyor, where they will be agitated and carried up by the lifting blade 60 until they roll off them to fall back into the water at the bottom of the drum and vat. By so falling, the vegetables will come in direct contact with the horizontal water sprays issuing from the nozzles 39 and be 65 driven forward by the impact, which at the

same time imparts a revolving motion to the vegetables around their own axis. The former are thereby subjected to the combined action of the water in the vat and from the nozzles and to combined rotating 70 and forward movements, so that when they reach the rear end of the drum they are perfectly clean and ready to be emptied by the discharge-blades onto the discharge-trough 24 and thence through the discharge chute 75 into baskets or other containers. It will be seen that the effect of the horizontal sprays in the relative positions indicated above is of great value and it forms one of the principal 80 features of this invention.

In the above description mention has been made of the use of this washing machine for tuberous vegetables; but it will be readily understood that the machine could be used for washing other goods, such as bones, 85 animal fats, etc.

While I have illustrated and described herein the preferred embodiment of my invention, and one which I have found by actual use to be very practical and efficient, 90 it may be found desirable after continued experience to make slight changes in the construction and arrangement of the details of my invention, and I intend to include in this application all such variations as fall 95 within the scope of the appended claims.

I claim:

1. The process of washing vegetables which consists in causing them to fall 100 through sheet-like sprays of water disposed substantially at right angles to the path of said falling vegetables and collecting them in a body of water.

2. The process of washing vegetables which consists in causing them to fall repeatedly through sheet-like sprays of water disposed substantially at right angles to the path of said falling vegetables thereby imparting to the latter a combined gyratory and linear motion, and collecting said vegetables in a body of water. 110

3. In a vegetable washing machine of the character described, a water container; a drum revolvably mounted therein and open at both ends; a plurality of longitudinally and radially disposed blades positioned within said drum and rotating therewith; longitudinally and angularly disposed discharging blades secured inwardly to the discharging end of said drum; means to introduce vegetables in said drum; means to discharge said vegetables therefrom; a supply of running water and means to inject a plurality of water sprays into said water container and above the level of the water 125 stored therein. 115

4. In a vegetable washing machine of the character described, a water container; a drum revolvably mounted therein and open at both ends; a plurality of longitudinally 130

- and radially disposed blades positioned within said drum and rotating therewith; longitudinally and angularly disposed discharging blades secured inwardly to the discharging end of said drum; means to introduce vegetables in said drum; means to discharge said vegetables therefrom; a supply of running water and a plurality of nozzles positioned above the level of the water stored in said container for injecting substantially horizontal sprays of water thereover.
5. In a vegetable washing machine of the character described, a water container; a 15 drum revolvably mounted therein and open at both ends; a plurality of longitudinally and radially disposed blades positioned within said drum and rotating therewith; longitudinally and angularly disposed discharging blades secured inwardly to the discharging end of said drum; means to introduce vegetables in said drum; means to discharge said vegetables therefrom; a supply of running water; a plurality of flattened 20 and horizontally disposed nozzles positioned above the level of the water stored in said container for injecting substantially sheet-like sprays of water thereover; automatic means to maintain said level of water in 25 said container, and means to drain said water therefrom.
6. In a vegetable washing machine of the character described, a water container; a 30 drum revolvably mounted therein and open at both ends; a plurality of longitudinally and radially disposed blades positioned within said drum and rotating therewith; longitudinally and angularly disposed discharging blades secured inwardly to the discharging end of said drum; means to introduce vegetables in said drum; means to discharge said vegetables therefrom; a supply of running water; a plurality of flattened 35 and horizontally disposed nozzles positioned above the level of the water stored in said container for injecting substantially sheet-like sprays of water thereover.

In testimony whereof I affix my signature.

RALPH HARVEY.
